UNITED STATES PATENT OFFICE.

MICHAEL HENRY, OF CHICAGO, ILLINOIS.

TIE-FASTENER.

1,388,259.

Specification of Letters Patent. Patented Aug. 23, 1921.

Application filed August 2, 1920. Serial No. 400,579.

To all whom it may concern:

Be it known that I, MICHAEL HENRY, a citizen of the United States, and a resident of the city of Chicago, county of Cook, and State of Illinois, have invented certain new and useful Improvements in Tie-Fasteners, of which the following is a specification.

My invention relates to improvements in tie fasteners, and has for its object the provision of a tie fastener upon which any four-in-hand tie may be easily draped and which is quickly and easily placed on a collar.

Other objects will appear hereinafter.

The invention consists in the combinations and arrangements of parts hereinafter described and claimed.

The invention will be best understood by reference to the accompanying drawings forming a part of this specification and in which,

Figure 1 is a rear view of the tie fastener,

Fig. 2, is a rear view with a part broken away,

Fig. 3, is a rear view with a portion in section to show the locking means,

Fig. 4 is a top plan view,

Fig. 5, is a view showing the arrangement of the tie on the fastener, and

Fig. 6, is a sectional view on the line 30 6-6 of Fig. 1.

The preferred form of construction consists in a metallic casing 1 having one end so bent outwardly as to form a flaring tongue 2. The flaring tongue 2 is rolled as at 3 to form a seat for a flexible member 4. Small metallic hooks 5 are attached to the protruding ends of said flexible member 4, said hooks being adapted to be hooked into the fabric portion of the tie, thus causing it to be draped about the flare. The casing 1 has a slot 6 extending throughout its entire length, said slot being adapted to contain a guide member 7. Attached to and extending in a lateral direction on each side of the top of the casing 1 are curved metallic members 8, said members being adapted to be placed under the flares of a collar to prevent the twisting of a tie and also to form arms upon which the tie is draped.

The guide member 7 is so bent that its central portion acts as a guide member and its ends are so bent as to form hooks 9. Below said hooks 9 is another set of hooks 10, the two sets 9 and 10 being adapted to be hooked into the fabric of the tie, thus assuring a snug fit about the casing. The casing 1 has

three openings 11, said openings being opposite the slot 6 and being of such diameter as to readily receive the head of a collar button. On the slotted side of the casing 60 and near its lower extremity, a wire loop 16 is attached, said loop being of such a size as to readily receive the narrow fly end of a four-in-hand tie.

Within the casing 1 is a metallic tube 12, 65 said tube 12 containing a slotted portion 13 which extends two-thirds its entire length, and a flaring end 14. On the opposite side of the tube from the slot 13 are openings 17, said slot and openings being adapted to 70 correspond to the slot and openings in the casing 1, in which the tube is mounted.

A spring 15 is fastened to the top of tube 12 and is adapted to engage the inner side of the top of the casing 1. The assembly 75 of the structure is as follows: The tube 12 is placed within the casing 1, slot 13 in said tube adjacent the slot 6 of the casing, and is pressed upwardly as far as the spring 15 will permit. The guide member 7 is then 80 placed in the slot 13 through the slot 6 and is made fast to the outer casing. The tube is then released and it is prevented from coming out of the casing by the guide member resting against the top of the slot 13. 85

The operation of the device is as follows: A tie is draped over the members 8 and about the casing 1, said tie being held snugly about the casing 1 by means of the hooks 9, 10 and 5. The narrow flare of the 90 tie is then pulled down through the loop 16. The tube 12 is then pressed upwardly until the openings 13 and 11 correspond; the members 8 are then tucked up under the flares of the collar and the collar button head is introduced into one of the openings 11; which of said openings being dependent on the height of the collar. The tube 12 is then released and the collar button becomes firmly wedged between the sides 95 of the opening in the tube and the casing.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 105 110 the appended claims.

Having described my invention, what I

claim as new and desire to secure by Letters Patent is:—

1. An article of the class described comprising a tubular casing having laterally extending tie-engaging arms; openings in said casing; means mounted within said casing adapted to engage a collar button head whereby said head may be locked in said openings, substantially as described.
- 10 2. An article of the class described comprising a casing having laterally extending tie-engaging arms on one end and flares on the opposite end; two or more openings in said casing; a slot opposite said openings; means mounted within said casing and cooperating with said slot and openings whereby a collar button may be locked in said openings and the locking means held within the casing, substantially as described.
- 20 3. An article of the class described comprising a casing having laterally extending tie-engaging arms on one end and flares at the opposite end; a tube slidably mounted in said casing an opening in said tube and in said casing and means whereby the tube and casing cooperate to lock said article upon a collar button in said openings, substantially as described.
- 30 4. An article of the class described comprising a casing having laterally extending tie-engaging arms on one end and flares at the opposite end; a tube slidably mounted in said casing, alined slots and apertures in said casing and tube; a spring mounted between the top of the tube and the inner side of the top of the casing; and limiting means mounted on said casing whereby the downward travel of said tube is limited, substantially as described.
- 40 5. An article of the class described comprising a casing having laterally extending tie-engaging arms on one end and flares at the opposite end; a tube slidably mounted in said casing; alined slots and apertures in said casing and tube; a guide member at-
- 45 tached to said casing and extending into the alined slots; a spring mounted between the top of the tube and the inner side of the top of the casing; and a laterally extending wire loop mounted on the slotted side of said casing, substantially as described.
- 50 6. An article of the class described comprising a casing having laterally extending tie-engaging arms on one side and flares at the opposite end; a tube slidably mounted in said casing; alined slots and apertures in said casing and tube; a spring mounted between the top of the tube and the inner side of the tubular casing; limiting means mounted on the casing and extending into the alined slots; a laterally extending wire loop mounted on the slotted side of said casing; a flexible member mounted on the base of the flared end; and hooks attached to the protruding ends of said flexible member, substantially as described.
- 55 7. An article of the class described comprising a casing having laterally extending tie-engaging arms attached to one end and flares at the opposite end; a tube slidably mounted in said casing; alined slots and apertures in said casing and tube; a spring mounted between the top of the tube and the inner side of the tubular casing; limiting means mounted on the casing and extending into the alined slots; a laterally extending wire loop mounted on the slotted side of said casing; a flexible member mounted on the base of the flared end, hooks attached to the protruding ends of said flexible member; and oppositely placed hooks on said casing between the top of the casing and the flared portion, substantially as described.

In testimony whereof I have signed my name to this specification in the presence of two subscribing witnesses.

MICHAEL HENRY.
